(57) **CLAIM**

The ornamental design for a safety lancet, as shown and described.

DESCRIPTION

FIG. 1 is a front perspective view of the safety lancet of the present invention;

FIG. 2 is a front perspective view of the safety lancet shown in FIG. 1 illustrating a cap attached thereto;

FIG. 3 is a front elevational view of the safety lancet shown in FIG. 1;

FIG. 4 is a rear elevational view of the safety lancet shown in FIG. 1;

FIG. 5 is a left side elevational view of the safety lancet shown in FIG. 1;

FIG. 6 is a right side elevational view of the safety lancet shown in FIG. 1;

FIG. 7 is a top elevational view of the safety lancet shown in FIG. 1;

FIG. 8 is a bottom elevational view of the safety lancet shown in FIG. 1; and,

FIG. 9 is a front perspective view of the safety lancet shown in FIG. 1, but with the lancet exposed through the aperture of the upper body.

The drawings illustrate a safety lancet. Contour lines are included in the various views of FIGS. 1-9 to depict surface curvature, flatness, beveling, or other shapes. FIG. 2 shows the transparent cap of the present invention attached thereto. The broken lines shown in FIG. 8 illustrate portions of the present invention form no part of the claimed design. The dash-dot lines shown in FIG. 7 illustrate boundary lines, and designate therein, portions of the present invention that form no part of the claimed design.
